COMBINED BEVERAGE DISPENSER AND FOOD SERVICE CARRIER

H. George Skaller, Flushing, N. Y.

Application March 25, 1957, Serial No. 45,418

Term of patent 14 years

(Cl. D14—3)

FIG. 1.

FIG. 2.

FIG. 3.

FIG. 4.

Fig. 1 is a perspective view of a combined beverage dispenser and food service carrier embodying my new design; Fig. 2 is a side elevational view thereof;

Fig. 3 is a side elevational view of the side opposite to that shown in Fig. 2; and

Fig. 4 is a rear elevational view thereof.

The characteristic feature of my design for a combined beverage dispenser and food service carrier resides in the configuration of the dispenser portion as shown.

I claim:

The ornamental design for a combined beverage dispenser and food service carrier, substantially as shown and described.
